UNITED STATES PATENT OFFICE.

PAUL O. UNGER, OF CHICAGO, ILLINOIS, ASSIGNOR TO WILSON-JONES LOOSE LEAF COMPANY, A CORPORATION OF ILLINOIS.

LOOSE-LEAF BINDER.

1,371,583.

Specification of Letters Patent. Patented Mar. 15, 1921.

Application filed December 16, 1918. Serial No. 266,948.

To all whom it may concern:

Be it known that I, PAUL O. UNGER, a citizen of the United States, and a resident of the city of Chicago, in the county of Cook 5 and State of Illinois, have invented certain new and useful Improvements in Loose-Leaf Binders; and I do hereby declare that the following is a full, clear, and exact description of the same, reference being had to 10 the accompanying drawings, and to the numerals of reference marked thereon, which form a part of this specification.

This invention relates to an improved form of a loose leaf binder wherein apertured clamping members are adjustably connected by flexible impaling posts, and has mounted in the ends thereof insets for rotatably supporting rollers which project outwardly through the apertures of said 20 clamping members to facilitate movement of the binder when in open position.

It is an object of the invention to construct a binder wherein apertured clamping members are provided with projecting rollers to permit easy movement of the binder 25 when in open position.

Other and further important objects of this invention will be apparent from the disclosures in the specification and drawings.

The invention (in a preferred form) is illustrated in the drawings and hereinafter more fully described.

On the drawings:

Figure 1 is a bottom plan view of a binder embodying the principles of this invention.

Fig. 2 is a rear end view thereof.

Fig. 3 is a side view of the binder partly 40 broken away and turned on end.

Fig. 4 is an enlarged detail section taken on line 4—4, of Fig. 1, showing parts in elevation.

Fig. 5 is an enlarged fragmentary top 45 plan view of the lower clamping member.

Fig. 6 is an enlarged section taken on line 6—6, of Fig. 4.

Fig. 7 is an enlarged detail section on line 7—7, of Fig. 6.

Fig. 8 is a section taken on line 8—8, of 50 Fig. 6.

Fig. 9 is a section taken on line 9—9, of Fig. 4.

Fig. 10 is a section taken on line 10—10, 55 of Fig. 6.

Fig. 11 is an enlarged section taken on line 11—11, of Fig. 4.

Fig. 12 is an enlarged fragmentary detail section taken on line 12—12, of Fig. 6, with parts omitted.

Fig. 13 is an elevational view of a portion of one of the chain binding posts removed from the binder.

Fig. 14 is an enlarged detail section on line 14—14, of Fig. 13.

Fig. 15 is a central vertical section taken through the outer end of one of the flexible posts, and showing parts in elevation.

Fig. 16 is an enlarged side elevation of one of the chain post links.

As shown on the drawings:

In the construction shown the reference numerals 1 and 2, represent the lower and upper covers of a loose leaf chain binder, having attached to the rear edges thereof by 75 means of hinges 3, lower and upper hollow clamping members or casings 4 and 5, respectively, which form a part of said covers.

The hollow clamping member 4, is made of two pieces of metal shaped as shown in 80 Fig. 11, and closed at the ends by end plates which are soldered or brazed thereto. The top wall of the clamping member 4, is provided near the ends thereof with post openings.

Secured within each end of the clamping member 4, is an insert 6, which may be constructed in any suitable manner, that shown, however, consisting of a plate stamped in a U-shape to fit in the end of the clamping member. A passaged block or 90 bushing 7, is securely mounted to the inside of each insert within the lower clamping member and is provided with a reduced neck 8, adapted to engage tightly in one of the post openings provided for the purpose in 95

the top wall of the clamping member 4, to hold the block in place. As clearly shown in Fig. 4, the lower or bottom wall of the clamping member 4, has an opening near each end thereof directly below concave recesses formed in the respective blocks 7, and the margins of said openings are curled or bent inwardly to engage in the recesses in the blocks 7, and form collars or rings 9,

affording pockets or recesses 10, for a purpose hereinafter described. The rear curved wall of the clamping member 4, is provided with an opening at each end thereof through 100 each of which a roller 11, projects. The rollers 11, are rotatably mounted on short axles 110

or pins 12, the outer ends of which are slotted to receive a screw driver to permit the reduced inner threaded ends of said pins to be threaded into threaded apertures provided for the purpose in the inner flanges of the channel inserts 6.

The hollow upper clamping member 5, is made of two pieces of metal shaped as shown in Fig. 9, and closed at the ends by end plates 10 which are soldered or brazed thereto. The bottom or inner wall of the clamping member 5, is provided near each end thereof with a post opening 13. Secured rigidly in the ends of the clamping member 5, are two upwardly directed channel braces or U-shaped inserts 14 and 15, respectively. The rear curved wall of the upper clamping member 5, is provided with an opening 16, at each end thereof through each of which a roller 17, projects. The rollers 17, are rotatably mounted on short axles or pins 18, the outer ends of which are slotted to receive the end of a screw driver to permit the threaded reduced inner ends of said pins to be threaded 20 into threaded apertures provided for the purpose in the inner flanges of the channel inserts 14 and 15. The two flanges of the channel insert 14, are each provided with an opening 19, near the inner edges thereof 25 through which the stem end 20, of a rotatable shaft projects. The outer end of the shaft stem 20, is squared as denoted by the reference numeral 21, and is positioned to allow a suitable key to be inserted through 30 an aperture or opening 22, in the end wall of the clamping member adjacent the bracket 14. The openings 19 and 22, are aligned with one another. The actuating shaft is disposed longitudinally in the 35 clamping member 5, near the inner or hinged wall thereof, and is threaded to afford a right thread portion 23, and a left thread portion 24.

Slidably disposed within the upper clamping member 5, are two bearing blocks 25, provided with transverse threaded passages near the inner ends thereof through which the right and left threaded shaft portions 23 and 24, respectively are threaded. The 40 bearing blocks 25, support the shaft in position to permit the same to project through an opening 26, provided for the purpose in the upright walls 27, of two stamped chain post guide members which are rigidly secured within the clamping member 5, to the 45 inside of the inserts 14 and 15. Each of the chain guide members embraces besides the upright wall 27, a downwardly curved guide tongue 28, the lower end of which is bent 50 to afford a flange or lug 29, which is spot welded or otherwise secured to a centrally apertured plate 30, integrally formed at an angle to the lower edge of the upright wall 27. The middle portion of the plate 30, 55 behind the aperture is depressed as denoted

by the reference numeral 31, to afford an elbow guide passage the upper end of which opens into an opening 26, formed centrally in the upright wall 27.

Connecting the upper clamping member 5, with the lower clamping member 4, are two link impaling posts or chain binding posts each constructed exactly alike and embracing an inner end anchor link comprising a slotted head 32, and an integral bolt or 70 stem 33, provided with a diametrical passage 34. The anchor bolts 33, project into transverse central passages formed in the bearing blocks 25, and are locked in position by means of retaining screws 35, which are 75 threaded upwardly through threaded passages 36, formed in said blocks at right angles and crossing through the central transverse passages in said blocks. The anchor bolt passages 34, register with the 80 threaded passages 36, to permit the screws 35, to project therethrough to hold the chain posts anchored to the bearing blocks. A plurality of pivotally connected interfitting links form a part of each chain binding post, 85 and as clearly shown in Fig. 16, each of said chain links is constructed to comprise an inclined bifurcated head 37, provided with a diametrical slot 38. A rib or tail piece 39, is integrally formed centrally on 90 the bottom of each link head 37, in a plane with the slot 38. A transverse passage or opening 40, is formed in the upper rear portion or corner of each of the link heads 37, at right angles to the slot 38. Formed transversely through the lower rear corner of each of the link tails 39, is an opening or 95 passage 41. The chain links are pivotally connected one to the other by means of link pins 42, as clearly shown in Figs. 13 and 14, 100 to permit the chain posts which have a diagonal break to bend or flex in one direction only. When the links are connected as shown the tail 39 of one link engages the slot 38 of an adjacent link so that the respective passages 41 and 40 of said links are 105 in register to receive one of the link pins 42. The inner end link of each post is pivotally connected to the head 32, of the anchor link, while the other end link of each 110 chain post is pivotally connected to an apertured tail piece integrally formed on one end of a longer cylindrical end link 44, provided with an axial threaded passage 45, in the other end thereof. Removably threaded into the threaded passage 45, of each of the end links 44, is a reduced threaded stem 46, of an extension link 47, which may be of any desired length, and is provided with an axial threaded passage 48, in the outer end thereof 115 to removably receive the threaded stem 49, of an enlarged knurled head or top piece 50.

Removably disposed between the binder covers 1 and 2, are a plurality of loose leaves 51, the binding margin of each of which is 120

provided with a plurality of slots to permit the chain posts to project therethrough for the purpose of removably clamping said loose leaves in position between the clamping members 4 and 5, as shown in Figs. 2 and 4. 5 The operation is as follows:

The loose leaves 51, are slotted at their binding margins to permit the same to be engaged on the chain binding or impaling posts. When sufficient leaves are disposed 10 between the binder covers 1 and 2, a binder key is projected into the opening 22, to engage on the squared tip or end 21, of the actuating shaft 23—24. By turning the key 15 the shaft is rotated thereby causing the bearing blocks 25, engaged thereon to move inwardly toward each other within the clamping member 5, to pull the chain posts upwardly and then inwardly toward each other 20 into locking or clamping position as shown in Fig. 4, wherein the knurled post heads 50, seat in the recesses 10, afforded by the collars 9, of the lower clamping member 4. The turning of the shaft acts to draw the 25 chain binding posts inwardly whereby the upper clamping member 5, and the lower clamping member 4, are tightly drawn toward one another securely clamping the binding margins of the loose leaves 51, there- 30 between.

The peculiar and novel construction of the chain post links permits the chain posts to break diagonally and bend along the pivoted sides thereof only. When the number of 35 loose leaves between the binder covers becomes too great for the length of the chain posts, the short extension links 47, may be removed and longer extension links substituted therefor.

40 As clearly shown in Fig. 12, the stamped chain post elbow guides 28—31, guide the chain posts at the bend or elbow and facilitate the operation thereof.

When the locked binder is positioned as 45 shown in Fig. 3, or in open position with

the rollers 11 and 17, resting on a table or desk, the binder may be very easily moved about on said table or desk, said rollers revolving on the roller pins 12 and 18, thus obviating scratching or marring of the table 50 or desk.

Referring to Figs. 8 to 11, inclusive, it will be noted that the clamping members 4 and 5, are each made of two metal members which are soldered or welded together 55 after the necessary operating parts have been assembled therein. The open ends of the casings formed by the metal members are closed by means of end plates which are soldered or welded to the end walls of the 60 inserts 6, 14 and 15, preferably before the latter are secured in the ends of the casings 4 and 5.

I am aware that numerous details of construction may be varied through a wide 65 range without departing from the principles of this invention, and I therefore do not purpose limiting the patent granted otherwise than necessitated by the prior art.

I claim as my invention:

70

1. The combination with a binder embracing clamping members, of covers pivotally connected thereto, and rollers mounted in said clamping members adapted to permit easy movement of said binder when open. 75

2. The combination with a chain post binder comprising apertured clamping members of covers hinged thereto, end inserts secured in said clamping members, and rollers in said clamping members supported by said end inserts and projecting through the apertures in said clamping members to facilitate movement of the binder. 80

In testimony whereof I have hereunto subscribed my name in the presence of a 85 subscribing witness.

PAUL O. UNGER.

Witness:

EARL M. HARDINE.
